US0D1084521S

(12) **United States Design Patent** (10) **Patent No.:** **US D1,084,521 S**
(45) **Date of Patent:** **** Jul. 15, 2025**

(54) **NAIL FILE**

(71) Applicant: **SOFIT Trade, s.r.o.**, Mestec Kralove (CZ)

(72) Inventor: **Jan Turina**, Podebrady (CZ)

(**) Term: **15 Years**

(21) Appl. No.: **35/521,992**

(22) Filed: **Jul. 17, 2024**

(80) **Hague Agreement Data**

Int. Filing Date: **Jul. 17, 2024**

Int. Reg. No.: **DM/239075**

Int. Reg. Date: **Jul. 17, 2024**

Int. Reg. Pub. Date: **Aug. 16, 2024**

(51) **LOC (15) Cl.** **28-03**

(52) **U.S. Cl.**

USPC **D28/59**

(58) **Field of Classification Search**

USPC **D28/56-59**

CPC **A61B 17/54; A45D 29/00; A45D 29/04;**

A45D 29/05; A45D 29/06; A45D 29/11;

A45D 29/14

See application file for complete search history.
